UNITED STATES PATENT OFFICE

LOUIS H. MORIN, OF NEW YORK, N. Y.

MACHINE FOR MAKING FLEXIBLE SHAFTING

Application filed April 15, 1927. Serial No. 183,972.

This invention relates to a machine for making flexible shafting such as is commonly used for transmitting torque to translating devices not in alignment or not rigidly secured together. It is essential that shafts of this type be flexible and yet resistive to torsion. To obtain this feature shafts of this nature are usually constructed by winding a layer of relatively fine wire around a center 5 or core-wire supported between two points, the convolutions being wound very closely together, and then winding a second and third or more layers around the core, each successive layer being wound in a reversed direction relatively to the preceding layer. By reversing the direction of winding of each successive layer a flexible shaft is formed which will be substantially capable of transmitting torque without submitting to torsion.

20 In accordance with this invention I propose to simultaneously wind a layer composed of a plurality of strands of wire around the core-wire and also to simultaneously wind a plurality of such layers around 25 said core-wire each successive layer being wound in a relatively reversed direction while continuously feeding the core-wire relatively to the point at which the layers are being laid upon said core, thus making it possible to manufacture substantially unlimited 30 lengths of cable in one continuous operation.

In accordance with this invention, I provide a machine which supports a core-wire under a constant tension and feeds it continuously relatively to a point of application where a layer of wire is wound thereupon. A plurality of rotary heads are suitably mounted to rotate around the core-wire to simultaneously lay a plurality of layers of 35 several wires each upon the core-wire, each successive head being rotated in a direction relatively reversed with respect to the previous head.

I will now describe with more particularity 40 a machine of my invention in connection with the drawings, which illustrate an embodiment of such a machine:

Fig. 1 is a plan view of a machine constructed in accordance with this invention; 45 Fig. 2 is a front elevation of the same;

Fig. 3 is an end elevation of the head or right end;

Fig. 4 is an enlarged plan of the head end;

Fig. 5 is an enlarged front elevation of the head end;

Fig. 6 is an enlarged elevation partly in section of one of the rotary heads;

Fig. 7 is a section on line 7—7 of Fig. 2;

Fig. 8 is a section on line 8—8 of Fig. 2;

Fig. 9 is a section on line 9—9, Fig. 1;

Fig. 10 is a rear elevation of that portion of the machine shown in Fig. 9, and

Fig. 11 is a detail of a portion of a cable illustrating the article made and the method of making the same.

The particular machine shown by way of illustration comprises a bed or frame 1 supported upon end and center legs 2, the bed 1 constituting a support for the core-wire feeding mechanism and also the layer winding 70 mechanism.

A spool 3 of the core-wire 4 is supported upon an angle bracket 5, (Figs. 4 and 5) rigidly secured to the bed 1 adjacent the right or head end thereof. Bracket 5 has 75 threaded thereinto a spindle 6 extending at right angles therefrom, which spindle is threaded upon its outer end to receive a spool retaining flange 7 and locking nut 8. Bracket 5 is formed with an extending ear 80 portion 9 which carries a spring friction device 10 adapted to contact against one flange of the spool 3 to resist rotation thereof, and is also formed with a second projecting ear portion 11 which carries a spring-pressed 85 guide and friction drag 12 for guiding the core-wire 4 as it is reeled off the spool 3 into and through the winding heads for winding a plurality of layers of wire around the core-wire. This guide and drag 12 comprises two 90 discs 13 (Fig. 4) mounted upon a stud 14 threaded into the ear portion 11 and resiliently urged together by a spring 15, carried by the stud 14. A nut 16 is threaded upon the stud 14 intermediate its ends and engages 95 spring 15 whereby through adjustment of the nut 16, the tension of spring 15 may be varied and the frictional resistance of the discs 13 acting upon the wire 4 may be adjusted to hold the proper tension upon the core-wire

100

as it is fed therefrom by the continuous feed-ing means.

After leaving the guide 12 core-wire 4 is passed through the center of the first of a series of five successive turrets or winding heads 18, 19, 20, 21 and 22 rotatably carried upon headstocks 23, 24, 25, 26 and 27 respectively, supported by the bed 1 in spaced relationship and adapted to wind successive layers of convolutions of wire around the core-wire, each of the five heads being constructed to carry and feed five strands of wire from five spools thereon. The five heads utilized in the illustrated machine are substantially the same in structure, each successive head being driven in a direction relatively reversed to the direction of rotation of the preceding head.

As the core-wire 4 leaves the first head 18 having had a layer of wire wound thereon it passes between and is engaged by the first of a series of five pairs of clamp-like gripping and feeding members, 28, 28^a; 29, 29^a; 30, 30^a; 31, 31^a and 32, 32^a supported upon two longitudinal parallel gripper cam shafts 33 and 33^a extending horizontally and substantially the full length of the machine. A pair of these grippers are positioned one on each of shafts 33 and 33^a adjacent the output end of each of the winding heads whereby the core-wire is gripped and fed as it leaves each winding head. The gripper members are all substantially similar in structure and are actuated by the shafts 33 and 33^a in such a manner and sequence that one gripper of each pair first grips and then feeds the core-wire, followed by a similar action of the other gripper of each pair with a slight overlap of feeding movements, i. e. each gripper seizes the core-wire and starts feeding before the other gripper of the same pair has let go, whereby the core wire is fed continuously and evenly under a constant tension while the winding heads are rotated about the core-wire and simultaneously wind successive layers of convolutions of wire around the core-wire.

Any convenient source of energy may be used to drive the machine and may be operationally connected to shaft 35 (Fig. 3) supported by bearing 36 bolted or otherwise secured to the end legs. Shaft 35 carries a pulley 37 over which a belt 38 passes also passing over a pulley 39 freely mounted on drive shaft 40 and adapted to be connected thereto by any convenient standard clutch 41 (Fig. 4). Drive shaft 40 is rotatively supported by outboard bearings 42 attached to the rear face of frame 1 at frequent intervals. A take-up pulley 43 is secured to the end of the right leg 2 to bear against and take up any slack in belt 38. Drive shaft 40 extends longitudinally of the machine and substantially the entire length thereof. A bevel gear 44 (Fig. 3) is keyed or otherwise

secured to drive shaft 40 opposite each of the winding heads 18, 19, 20, 21 and 22. Each gear 44 engages a coacting bevel gear 45 rotatably mounted on the end of a stub shaft 46 carried by a bracket 47 fastened to the machine bed adjacent each of the head stocks 23, 24, 25, 26 and 27. Gears 44 associated with heads 18, 20, and 22 are mounted upon one side of gears 45 while the gears 44 associated with heads 19 and 21 are mounted upon the other side in order to have heads 19 and 21 rotated in an opposite direction from heads 18, 20, and 22.

Bevel gear 45 has secured thereto, or formed integral therewith, so as to rotate therewith, a spur gear 50 which meshes with spur gear 51 constituting one end of a train of removable gears carried by studs 52 and 53 adjustable in slotted arms 54, the train terminating in a spur gear 55 fast upon the outer end of a transverse shaft 56 rotatably supported by bearings 57 in an extending housing 58 projecting from each of the head stocks. By means of the adjustable studs various sizes of spur gears may be inserted in the train of gearing to produce any desired driving ratio between spur gear 51 and spur gear 55. The inner end of transverse shaft 56 carries a bevel gear 59 which meshes with another bevel gear 60 fast upon the turret or head shaft 61 intermediate the ends thereof, the turret shaft being supported at its ends by the taper roller bearings 62 mounted in the two ends of each of the head stocks. It is readily seen that whenever energy is applied to shaft 35 shaft 40 is driven if clutch 41 is engaged and shaft 40 will drive each of stub shafts 46 and through the associated train of removable gears will drive shaft 56 and through it will rotate the turret shaft 61.

One end of the turret shaft 61 terminates in a flange 63 to which is rigidly secured one of the spool supporting discs 64. A second disc 65 of substantially the same diameter is secured to disc 64 in parallel spaced relationship thereto by means of spacing ferrules 66 and bolts 67. Between the two discs are mounted five spindles 68 upon which spools of wire 69 may be rotatably mounted. Adjacent each spool spindle 68 and also extending between the two discs 64 and 65 there is a spring friction guide and drag 70 similar to that described in connection with the take-off of the core-wire 4 from the core spool 3, and over which the wire passes as it leaves the spools to be wound around the core-wire.

In order to guide the strands of wire as they come off the friction guides preparatory to winding them around the core-wire, there is bolted to disc 64 a ring 71 having studs 72 projecting therefrom, which studs are bored transversely as at 73 to form guiding apertures leading toward the axis of the disc and through which the wires are passed. At

the center of disc 64 there is also secured a cylindrical sleeve 74 bored longitudinally as at 75 to the exact size of the core-wire in accordance with the particular head to which the sleeve is attached. Sleeve 74 is also bored radially at five points spaced axially along the sleeve to provide guiding apertures 76 through which strands of wire are passed to guide them accurately to the core-wire thus causing the five wires to lay closely adjacent each other in one single layer upon the core-wire as the head is rotated around the core-wire. Thus as the five heads are rotated about the core-wire the five strands of wire will be reeled off the five spools on each head and wound around the non-rotating core-wire under a constant tension to form a plurality of reversely wound layers of wire thereon while the core-wire is being constantly fed axially through the heads.

Drive shaft 40 (Figs. 1, 4, 9 and 10) also has a beveled gear 79 secured thereto near the right end thereof, which engages with a co-acting bevel gear 80 fast on the end of a cross shaft 81 rotatably supported in pedestal bearings 82 and having a worm 83 keyed to its other extremity. Worm 83 drives a worm wheel 84 slidably keyed to gripper cam shaft 33^a, and mounted in housing 85 bolted or otherwise secured to the frame, which housing prevents worm wheel 84 from moving laterally of the shaft. It follows therefrom that shaft 33^a will be driven from shaft 40 and will in turn drive gripper cam shaft 33 through spur gears 86^a and 86 secured to the ends of shaft 33^a and 33 respectively, gear 86^a being of sufficient width to permit axial movement of both shafts without resulting in disengagement of the gears.

The gripper feeding mechanism is shown particularly in Figs. 1 and 7, wherein it will be seen that a pair of gripper members are attached to shafts 33 and 33^a after each turret or head with one gripper of each pair secured to and actuated from shaft 33 and one from shaft 33^a, i. e. immediately adjacent head 18, gripper 28 is attached to shaft 33 and gripper 28^a to shaft 33^a in staggered relationship. Each gripper comprises a carriage member 90 having a stationary upper jaw and a slide member 91, slidable in the carriage member. The carriage member terminates at its upper end into a jaw member 92, which may be faced with a wear plate 93, and terminates at its lower end into a cylindrical boss 94, which is bored to rotatably fit cam shafts 33 or 33^a. A collar 95 is pinned to shafts 33 and 33^a upon each side of the boss 94, to prevent axial movement between the shafts and the carriages. Intermediate the two extremities and laterally displaced therefrom the carriage has formed thereon a boss 96 which is longitudinally bored to receive steadyng shafts 97 or 97^a which serve to prevent the carriage from rocking upon rotation of shafts 33 and

33^a, and are supported by brackets 98 fastened to the side of the bed of the machine.

The lower slide member 91, is dovetailed to the inner surface of the carriage 90 so as to slide vertically thereon and has a clamping jaw 99 adjustably secured to the upper ends thereof which contacts with the wear plate 93, secured to the carriage members when the slide is in its upper or closed position. The lower end of the slide terminates into bifurcated lugs 100 through which a pin 101 passes rotatably supporting a cam roller 102. Cam rollers 102 engage with cams 103, 103^a immediately below and keyed to shafts 33 and 33^a. The high points of the two cams 103, 103^a are diametrically opposite each other thus causing one gripper of each pair to be in gripping position while the other gripper of each pair is in open position. The slides 91 are normally urged to their open position by spring 104 positioned in a recess in the carriage members 90, and are under compression between the bottom of the recesses and the pin 105 riveted to and projecting inwardly from the slide members. It follows therefore that as shafts 33, 33^a rotate the grippers will be alternately opened and closed upon the core-wire 4 through the action of cams 103, 103^a and rollers 102.

Feeding movement or axial movement (see Fig. 4) is imparted to the grippers and shafts 33 and 33^a through the medium of a gear 106 slidably keyed to shaft 33^a so as to rotate therewith but slide axially thereupon. Gear 106 is restrained from axial movement by a housing 107 fastened to the bed of the machine and meshes with gear 108 fast upon an end of a short shaft 109 mounted in pedestal bearings 110. Shaft 109 carries a bevel gear 111 secured thereto intermediate its ends, which engages a bevel gear 112 fast upon one end of a cam shaft 113 supported by pedestal bearings 114 at each end thereof bolted to the bed of the machine. Cam shaft 113 is transversely disposed to the two gripper arm shafts 33 and 33^a and has two cams 115 and 115^a secured thereto, one adjacent each of shafts 33 and 33^a respectively, and have their respective high points diametrically opposite each other.

Cams 115 and 115^a engage two cam rollers 116 and 116^a pivoted between the bifurcated ends of two slide members 117 and 117^a which are dovetailed for sliding movement into blocks 118 and 118^a fastened to the bed of the machine. Slides 117 and 117^a are attached to yokes 119 and 119^a which form the end bearings and supports for the right end of shafts 33 and 33^a and gears 86 and 86^a respectively, the ends of said shafts fitting within the yokes to permit rotation therein but being threaded upon their extremities to receive nuts 120 and 120^a which prevent the shafts from moving axially in the yokes. Slides 117 and 117^a are constantly urged to

ward the left so as to maintain contact of rollers 116 and 116^a with cams 115 and 115^a by springs 121 and 121^a mounted on rods 122 and 122^a under compression between the slides 117 and 117^a and adjusting nuts 123 and 123^a upon rods 122 and 122^a. Rods 122 and 122^a are supported by brackets 124 and 124^a fastened to the end of bed 1 of the machine.

It follows that as shaft 33^a is rotated by 10 worm 83 and worm wheel 84 and in turn rotates shaft 33 through gears 86 and 86^a, the short shaft 109 will be driven through gears 108 and 106 and will in turn drive cam shaft 113 thereby rotating cams 115 and 115^a 15 and impart alternate reciprocating movements to shafts 33 and 33^a and the gripper members carried thereby.

For convenience in controlling the machine the clutch 41 is controlled by a lever 125 pivoted intermediate its ends to the frame and extending to the front of the machine where it terminates and engages in a slot in the end of an arm 126 secured to a long rod 127 running the full length of the machine and supported by brackets 128 bolted to the side of the machine bed. An operator therefore may start and stop the machine from any point along the machine by moving the rod 127 to the right or left as the situation required to 30 either start or stop the machine.

In making flexible shafts with the machine illustrated the machine is first prepared by placing a spool 3 of core-wire 4 of suitable size upon the spindle 6 supported in bracket 25 5 and other spools of suitable layer wire are placed upon each of the five spindles 69 on each of the five heads 18, 19, 20, 21 and 22. The core-wire is then passed between the discs 13, the guide and drag 12 and through 40 the center of the first head 18 and its associated feeding grippers 28 and 28^a, and thence through the remaining heads and grippers. The five strands of wrapping wire from the first head 18 are then led in from the spools 45 through their respective drags and guides and are attached to the core-wire 4 by soldering or otherwise. The clutch 41 is then engaged and the machine is run until the point on the core-wire whereon the first five strands 50 were attached has just passed through the second head 19 whereupon clutch 41 is disengaged and the machine is stopped. The five strands from the spools or head 19 are then attached and the machine is again started 55 and the series of operations just outlined are repeated until all the strands of wire from all the spools on all the heads have been attached after which the machine is run continuously until the desired length of flexible 60 shaft has been made.

With the machine running normally the core-wire is fed continuously and under constant tension by the grippers, those on shaft 33 pulling steadily and alternately with those 65 on 33^a. Simultaneously with the feeding ac-

tion the heads 18, 20, 22 are being rotated around the core-wire and are winding their respective layers of five strands of wire each on the core in one direction while the heads 19 and 21 are winding their respective layers of five strands each in the relatively reversed direction. Thus the flexible shaft is made by continuously feeding a core-wire and simultaneously winding thereon successive layers, of several strands each, of wire thereon, each successive layer being wound in a relatively reversed direction. 70 75

It is obvious that any number of spool spindles may be provided on each winding head to wind any desired number of strands per layer and also that any number of heads may be employed and that many other changes may be made in the details without departing from the spirit and scope of the invention as defined in the appended claims. 80 85

I claim:

1. A machine for making flexible shaft, including means for progressively feeding a core-wire, a plurality of rotatable heads revolving about said core for guiding a plurality of layers of wires, means for positively rotating said heads at predetermined and different speeds of rotation to cause them to wind a plurality of layers of wires around said core as it is being progressively fed, including means for independently varying the speed of rotation of each of said heads. 90 95

2. A machine for making flexible shaft, including means for progressively feeding a core-wire, a plurality of rotatable heads disposed radially around said core wire and revolvable about said core as an axis for winding a plurality of wires around said core, means for simultaneously and positively rotating said heads at predetermined and varied speeds of rotation in relatively reversed directions to cause them to lay a plurality of layers of wire around said core while said core is being progressively fed including means for independently varying the speed of rotation of each of said heads. 100 105

3. A machine for making flexible shaft, including a plurality of grippers for alternately gripping and continuously feeding the core-wire and a plurality of rotary heads revolvable about said core-wire as its axis for guiding and laying a plurality of wires around said core-wire. 110 115

4. A machine for making flexible shaft, including a plurality of grippers for alternately gripping and continuously feeding a core-wire and a plurality of rotary heads revolvable about said wire for laying successive layers of wire around said core-wire. 120

5. A machine for making flexible shaft, including a plurality of grippers for alternately gripping and continuously feeding a core-wire and a plurality of rotary heads revolvable about said wire for laying successive layers of wire around said core-wire, and means 125 130

for rotating each successive head in a reverse direction relatively to the preceding head.

6. A machine for making flexible shaft, comprising a support for a core-wire, a plurality of rotary heads revolvable about said core-wire, means for driving said heads, means for continuously feeding said core-wire including a pair of rotatable and slideable shafts and a gripper attached to each shaft and actuated thereby to alternately grip and feed the core-wire.

7. A machine for making flexible shaft, comprising a frame, a support for a core-wire, a plurality of rotary heads for laying a plurality of layers of wire upon said core-wire, a driving shaft for rotating said heads about said core-wire, grippers for continuously feeding said core-wire, a cam shaft for actuating said grippers actuated from said first mentioned shaft whereby the core-wire is fed while the heads are rotated there-around.

8. A machine for making flexible shaft, including means for progressively feeding a core-wire, a plurality of rotatable heads revolving about said core for guiding a plurality of layers of wires about said core, and means for independently varying the speed of rotation of each of said heads.

In witness whereof, I hereunto subscribe my signature.

LOUIS H. MORIN.
